A new *Petunia* plant particularly distinguished by red flowers with darker red veins and a trailing plant habit, is disclosed.

1 Drawing Sheet

1

Genus and species: *Petunia x atkinsiana* (syn. *P. x hybrida*).
Variety denomination: 'KLEPH24743'.

BACKGROUND OF THE NEW PLANT

The present invention comprises a new and distinct variety of *Petunia*, botanically known as *Petunia x atkinsiana* (syn. *P. x hybrida*) and hereinafter referred to by the variety name 'KLEPH24743'. 'KLEPH24743' is a selection from a controlled cross between the proprietary female *Petunia* line 'Easy Wave F1 Red Impr.' (not patented) and the male *Petunia* line 'Surfinia Red Trailing 2018' (not patented).

In July of 2019, the proprietary female *Petunia* line 'Easy Wave F1 Red Impr.' and the proprietary male *Petunia* line 'Surfinia Red Trailing 2018' were cross pollinated in Latina, Italy and seeds were obtained. The seeds were sown and plants were grown for evaluation. A plant line was selected in April 2020 in Latina, Italy and named 'KLEPH24743'. In May 2020, 'KLEPH24743' was first vegetatively propagated by terminal tip cuttings and tissue culture in Latina, Italy. 'KLEPH24743' was found to reproduce true to type in successive generations of asexual propagation via tissue culture and terminal tip cuttings.

SUMMARY

The following are the most outstanding and distinguishing characteristics of this new variety when grown under normal horticultural practices in Latina, Italy.

1. Red flowers with darker red veins; and
2. Trailing plant habit.

DESCRIPTION OF THE PHOTOGRAPH

This new *Petunia* plant is illustrated by the accompanying photograph, which shows a close-up of the flower of the plant. The plant is about ten weeks old grown in Stuttgart,

2

Germany in May 2022. The colors shown are as true as can be reasonably obtained by conventional photographic procedures.

5 DESCRIPTION OF THE NEW VARIETY

The following detailed descriptions set forth the distinctive characteristics of 'KLEPH24743'. The data which define these characteristics were collected from asexual 10 reproductions carried out in Latina, Italy. Data was collected on thirteen-week-old plants grown indoors in Latina, Italy 15 under greenhouse conditions in May 2025. Color references are to The R.H.S. Colour Chart of The Royal Horticultural Society of London (R.H.S.), 5th edition (2007).
